UNITED STATES PATENT OFFICE

ALEXANDER BENFORADO, OF NEW YORK, N. Y.

LADY'S HAND BAG

Application filed May 5, 1930. Serial No. 449,804.

The present invention relates to improvements in ladies' hand bags, and more particularly to hand bags of the envelop type.

The main object of the invention is to provide a hand bag of this type with a compartment disposed exteriorly of the main bag in which articles habitually used may be held and to which access may be had without having to open the main bag.

Another object of the invention is to mount within the said compartment a plurality of receptacles, and to so combine the same with the closure frame of the said compartment that the said receptacles are swung out from said compartment when said closure frame is shifted to open position, whereby ready access may be had to the articles within said receptacles.

A further object of the invention is to provide a lady's hand bag of the type mentioned which is simple in construction, durable in use and capable of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

One of the many possible embodiments of the invention is illustrated in the accompanying drawings, in which:—

Figure 1 is a front elevation of a hand bag embodying the improvements, both the closure frame and the main flap of the bag being shown in open positions; Fig. 2 is a section

taken on line 2—2 of Fig. 1, the main flap of the bag being folded toward the rear face of the bag; and Fig. 3 is a section similar to the one shown in Fig. 2 with the closure frame swung toward closing position.

In the drawings the numeral 10 indicates the front member and the numeral 11 the back member of a bag, the said elements being made of cloth or flexible leather, or other suitable flexible material, they being united along their side edges by gussets 12, to form the main compartment 13 of a hand bag, the said gussets being folded as usual in constructions of this type and serving as the means whereby the size of the main compartment may be varied according to the requirements. With the back member 11 is preferably made integral a flap 14, which is adapted to be bent over and lie in front of and adjacent to the front member 10, to close the bag. The flap is provided with a tab 15, carrying the element 16 of a separable fastener, the other element co-operating therewith, denoted by the numeral 17, being attached to the front member 10. By means of these separable fastener elements the flap is removably secured to the said front member when the bag is closed.

To the inner face of the front member 10 is secured in any suitable manner a shallow tray 18, extending into the main compartment 13 and forming a supplemental compartment which is adapted to be closed by a closure frame 19, hinged at 20 in any suitable manner to the outer face of the front member 10 along the lower longitudinal edge 21 of the tray. This tray is of oblong configuration, as clearly shown in Fig. 1 of the drawings. The closure frame is provided with a flap 22, carrying an element 23 of a separable fastener, the other element, denoted by the numeral 24, being secured to the front member 10. When the last-mentioned separable fastener elements are engaged, the closure frame 20 is held in its closing position.

Adjacent the lower longitudinal edge 21 of the tray are hinged to the latter a plurality of receptacles 25, each having an open mouth so that articles which are frequently or habitually used may be conveniently inserted into the same. In the case illustrated in the drawings, one of these receptacles is shown to hold cigarettes 26, and the other one a match book 27 and a cigarette holder 28. Each of these receptacles is connected by a flexible strip 29 with the closure frame 19. One end of each of these strips is attached in any suitable manner, for instance by an eyelet 30, to the top portion of one of the receptacles 25, and at its other end to that longitudinal edge portion of the closure frame which is hinged to the front member 10 of the bag. The length of each strip 29 is such that the receptacles 25 are swung around their hinges out of the tray 18, as shown in Fig. 2 of the drawings, when the closure frame is swung toward open position approximately 180 degrees around its hinge, the weight of the receptacles 25 swinging them back into the tray when the closure frame is swung toward closing position, as shown in Fig. 3 of the drawings. It will be noted from Fig. 2 of the drawings that the vertical wall of the tray limits the outward movement of the receptacles 25 when the latter are shifted around their hinges by swinging the closure frame 19 toward open position.

When the elements are in the positions shown in Fig. 2 of the drawings the articles within the receptacles 25 can be readily taken hold of by the user, the said articles not only projecting above the said receptacles but being outside of the tray 18.

It is obvious that, while herein a main bag of specific configuration and construction has been described, the improvement herein specified may be combined with bags of other types without departing from the invention, which lies mainly in the provision of a supplemental compartment combined with a closure frame which is so connected with receptacles within the supplemental compartment that the said receptacles are swung out from said compartment as the closure frame is shifted toward open position. Attention is called to the fact that, while herein receptacles holding specific articles have been described, receptacles of any other shape and configuration may be made use of according to the articles to be stored therein.

What I claim is:—

A lady's hand bag including front and back members connected together to form a main compartment, a flap connected to the back member along its top edge and adapted to be bent over and lie in front of said front member to close the bag, a tray on said front member extending into said main compartment and forming an open supplemental compartment, a closure frame hinged to said

front member for closing said supplemental compartment, a plurality of open receptacles hinged to said tray adjacent to said closure frame hinge, and flexible connections between said closure frame and said receptacles whereby the latter are swung around their hinges out of said tray when said closure frame is moved toward opening position, said tray limiting the outward movement of said receptacles.

Signed at New York, in the county of New York, and State of New York, this 21st day of April, A. D. 1930.

ALEXANDER BENFORADO.
